UNITED STATES PATENT OFFICE.

FRANKLIN ELIAS RANDEL, OF NEW YORK, N. Y.

HAT-SWEAT.

SPECIFICATION forming part of Letters Patent No. 351,402, dated October 26, 1886.

Application filed August 6, 1886. Serial No. 210,222. (No model.)

To all whom it may concern:

Be it known that I, FRANKLIN ELIAS RANDEL, a citizen of the United States, residing at New York, in the county of New York and State of New York, have invented new and useful Improvements in Sweat-Leathers for Hats, &c., of which the following is a specification.

My invention relates to the sweat leathers or bands of hats, caps, &c.; and the object of my invention is to produce a sweat-band which shall be variable in length, so as to vary the size of the hat, and which shall be as light and comfortable to the wearer as an ordinary sweat-band.

To the above purposes my invention consists in certain peculiar and novel features of construction and arrangement, as hereinafter described and claimed.

In order that my invention may be fully understood, I will proceed to describe it, with reference to the accompanying drawings, in which—

Figure 1 is an under side perspective view of a hat with my improved sweat-band applied thereto, the said sweat-band being turned outward to display its construction. Fig. 2 is a detached view of the sweat-band. Fig. 3 is a view similar to Fig. 2, but looking at the opposite end of the sweat-band.

In the said drawings, *a* designates the sweat-band, which may be of leather, or of any other suitable or preferred material, as desired. This band is stitched or otherwise secured in proper position within the hat; but instead of being attached to the hat throughout its length, as is usually the case, the ends *a'* *a''* are left free, an extra piece of material, as at *b*, being secured in the space left by the free ends of the band.

The ends *a'* *a''* of the band may be tapered off or reduced in width, as shown, if desired; but while this is preferable, it is not essential to the operation of my invention. The free end *a'* carries a hook, *c*, the stem *c'* of which is formed of flexible material, for a purpose

to be hereinafter explained. The free end *a''* is formed with any desired number of holes *a'*, which are strengthened by a re-enforce piece, *d*, perforated with a corresponding series of holes, *d'*, the opening in the free end *a''*, which receives the hook *c*, being also strengthened by a re-enforce piece, *e*.

From the above construction it will be seen that if the hat is too large for the wearer the defect will be perfectly remedied by engaging the stem in one or the other of the holes *a'*, and that the size of the hat may be virtually enlarged by moving the hook in the opposite direction. Thus the desired variations in size may be readily made without discomfort to the wearer, and without inconvenient handling of the band or leather. When the hook *c* has been inserted into the required hole, its end is to be slightly pressed or squeezed, so that, owing to the flexible character of the hook, the ends of the band may be readily and firmly secured together.

Having thus described my invention, what I claim as new, and desire to secure by Letters Patent, is—

1. The sweat leather or band provided with the free ends *a'* *a''*, in combination with the supplemental piece *b*, secured to the hat at a point where the said ends meet, and the attaching means to fasten the two ends *a'* *a''* together, as set forth.

2. The combination, with a hat, cap, or similar article, of the band *a*, secured thereto so as to leave the free ends *a'* *a''*, the supplemental piece *b*, secured to the hat, the hook *c*, and re-enforce piece *e* upon end *a'*, and the holes *a'*, and re-enforce *d*, secured to end *a''*, substantially as set forth.

In testimony that I claim the foregoing as my own I have hereto affixed my signature in presence of two witnesses.

FRANKLIN ELIAS RANDEL.
